UNITED STATES PATENT OFFICE.

SAMUEL H. FISH, OF HINSDALE, ASSIGNOR OF ONE-HALF TO HENRY C. MIDDAUGH, OF CLARENDON HILLS, ILLINOIS.

POTATO-PLANTER.

SPECIFICATION forming part of Letters Patent No. 505,877, dated October 3, 1893.

Application filed October 25, 1890. Serial No. 369,355. (No model.)

To all whom it may concern:

Be it known that I, SAMUEL H. FISH, a citizen of the United States, residing at Hinsdale, in the county of Du Page and State of Illinois, have invented a certain new and useful Improvement in Potato-Planters, (Case No. 11,) of which the following is a full, clear, concise, and exact description, reference being had to the accompanying drawings, forming a part of this specification.

My invention relates to potato planters of the class illustrated and described in my Patent No. 414,148, granted October 29, 1889.

My invention herein relates more particularly to the dropping mechanism, and I contemplate transmitting power to the dropping mechanism by means of sprocket wheels and a pitman after the manner described in my said patent.

The mechanism for throwing the machine into and out of gear may be the same as that claimed in my said patent.

In the practical operation of my patented machine I find that sometimes one of the pockets in the revolving cylinder would fail to fill and at other times a pocket would become clogged so as to drop two or three pieces at once, and speaking generally, the object of my invention herein is to prevent such uncertainty in the operation of the machine and provide a mechanism by which the potatoes may be dropped in drills evenly and at uniform distances apart.

More particularly my invention consists, first, in a stationary pocket and means for transmitting one or more potatoes from the hopper thereof to be in position to be taken up by the fork fingers; second, in a cam for operating the fork fingers and means for imparting to said cam a limited rotary movement upon its shaft to withdraw one fork to permit the seed for one hill to drop while another fork is caused to take hold of the seed for another hill; third, in the construction whereby a receptacle is provided between the hopper and the pocket for a supply of seed, and reciprocating pieces adapted to move the seed in said receptacle toward the dipper which is operated to fill the pocket from the receptacle, said pieces being preferably yielding; fourth, in a weighted pivoted stop car-

ried by the reciprocating slide and adapted to be brought into position to prevent the seed from accumulating or becoming clogged at the dipper; fifth, in an arm lever rigidly connected to the shaft on which the cam is mounted and adapted to be operated by stops carried upon the reciprocating slide to insert and withdraw the forks by giving the cam the desired limited rotary movement back and forth; sixth, in a spring actuated plate carried by the slide, in combination with a trigger arranged to release the plate and permit the same to be thrown forward to clear away any surplus seed that may have been carried back beyond the pocket; seventh, in the disk moved step by step by a pawl upon the reciprocating slide through which disk the forks are inserted; eighth, in the means for holding the disk from turning during the forward stroke of the reciprocating slide; and, ninth, in certain details of construction and combination of parts hereinafter more particularly described.

My invention will be more readily understood by reference to the accompanying drawings, in which—

Figure 1, Sheet 1, is a side elevation of a potato planter embodying my invention. Fig. 2, Sheet 2, is a plan view thereof. Fig. 3, Sheet 3, is a side elevation as seen from central section line $x-x$ of Fig. 2, the slide, however, being shown thrust forward. Fig. 4 is a detailed side view of the cam for operating the forks. Fig. 5 is a detailed view of the fixed plate provided with the notch which limits the movement of the cam. Fig. 6 is a view showing certain of the parts illustrated in Fig. 3 in the position which they assume when the slide is thrust back. Fig. 7 is a view of the shovels in the receptacle below the hopper as seen from sectional line $y-y$ of Fig. 1. Fig. 8, Sheet 5, is a view upon line $x-x$ of Fig. 2, the slide being forward. Fig. 9 is an elevation showing the manner of mounting the forks in their cam at the rear of the fork disk. Fig. 10, Sheet 6, is a view showing the same parts illustrated also in Fig. 8 in the position which they assume when the slide is thrust back. Fig. 11 is a transverse vertical sectional view upon line $z-z$ of Fig. 2.

Like parts are indicated by similar letters of reference throughout the different figures.

I would say at the outset that the means for imparting a reciprocating movement to the pitman *a* forms no part of my invention herein, and therefore I will not describe the same further than to state that the sprocket wheels and chain and the means for throwing the machine into and out of gear, the plow for making the drill and the shovels for covering the potatoes have been described in my patent of October 29, 1889. I have then the pitman *a* pivoted to the reciprocating slide *b* as shown at *c*. In this manner power is transmitted to the dropping mechanism as the machine is drawn along and the potatoes placed in the hopper *d* are taken out a few at a time and carried into position to be taken up by the dipper *e* and emptied from the dipper into the pocket *f*, and the forks *g* are inserted successively through the disk *h* carrying the same, into the pocket to take out one or more, that is, sufficient seed to plant a hill. At each backward stroke of the reciprocating slide *b* the pawl *i* carried upon the slide engages with a notch upon the disk *k* which disk *k* is rigidly connected with fork disk *h* and thus the fork disk is carried backward step by step at each reciprocation of the slide *b*. The shorter arms of the forks are carried in the cam groove *l* moving during the backward stroke of the slide but being held from rotary movement by an automatically actuated dog *m* during the forward stroke of the reciprocating slide; this dog is normally thrust forward toward the notched disk *k* by a spring; a bell crank lever *n* pivoted as shown is operated by a trigger device *o* carried upon the slide; this trigger device as the slide begins to move backward comes against an inclined projection or lug upon the bell crank to turn the bell crank upon its pivot and thereby withdraw the dog *m* from the notch just as the pawl *i* is about to take another notch of the disk *k*; while therefore the slide continues its backward movement the disk is turned backward by the pawl, the dog *m* in the meantime riding upon the periphery of the disk ready to take the next notch at the completion of the backward stroke. I have then the fork disk and the forks rotated a single step at each backward stroke of the slide *b* and the said disk is held from rotary movement at other times. It is necessary, however, that the forks shall be operated by the cam at a time when the disk is thus held from rotary movement. I therefore provide for giving the cam itself a limited rotary movement at the proper time, this rotary movement of the cam being limited by a notch provided in the plate *p*. Thus as shown in Fig. 5 a pin projecting from the cam rests in the notch of stationary plate *p*, the cam is mounted rigidly upon its shaft, the arm *q* is also rigidly connected with the same shaft, and thus by providing pins *r* *s* upon the slide in position to come

against the arm at the proper times the cam is itself moved back and forth to operate the fork opposite the pocket when filled and the fork that is in position to drop the seed which it has carried back, and thus while the slide is going forward the cam is moved by the pins *s* coming against the arm *q* and the groove of the cam is of such shape that the forward rotary movement imparted thereto will cause one fork to close and take the seed in the pocket and the opposite fork, that is the one over the hollow shoe, to open and drop the seed. The return stroke of the slide causes the pin *r* to come against the arm *q* again and thus the cam is carried back to its other position. Thus the forks have a rotary step by step movement and also an inward and outward movement. As each fork comes up opposite the pocket it closes and remains closed until it is carried by its rotary movement over the hollow shoe and thereupon it is opened, dropping the seed, and stays open empty until it is again brought opposite the pocket. Thus the different forks act in succession.

I have thus described the operation of the forks in dropping the potatoes. I have also stated the fact that the potatoes are transferred from the hopper to the pocket preparatory to being picked up by the forks.

I will now proceed to describe more in detail the means for getting the seed from the hopper into the pocket.

Attached to the reciprocating slide are agitators *t* which move between the potatoes in the hopper and the sides of the hopper as the slide is reciprocated. The opening from the hopper into the receptacle *u* between the hopper and the pocket is of sufficient size to permit the potatoes when thus stirred by the agitators to enter the receptacle *u* in limited quantities. This receptacle *u* may be considered as the dividing chamber, that is the place where a few are singled out from the mass. The shover *a'* is mounted upon a pivotal shaft *a²* and normally held in the position shown by the spring *a³* coiled up on said shaft. As the slide *b* is carried forward the levers *a⁴* connected between the slide and the shover are caused to act upon the shover and drive it backward to carry any potatoes that have fallen from the hopper into the separating chamber *u* backward to the dipper *e*, that is over the dipper *e* as shown in Fig. 8. If the shover should meet with undue obstruction in its passage backward, being mounted upon a pivot held in position by a spring, the shover will yield when the obstruction is sufficient to overcome the opposing force of the spring *a³*. The shover is thus carried back and forth in the separation chamber at proper times so as to insure the filling of the dipper. The shover preferably consists of three triangular plates as shown. When the shover returns toward the front of the machine it is so shaped that it may pass under any potatoes that may be in its path. The swinging plate *a⁵* is pivoted to the reciprocating slide *b*.

as shown, and thus as the shover is carried in one direction the plate is carried in the other. The plate a^5 and the shover a' thus act together in carrying the seed to the dipper, 5 that is, the shover carries the seed toward the dipper and the plate a^5 passing over the top of the shover throws back any surplus of seed. When the plate a^5 is carried backward, if its free end meets with any obstruction, 10 it is swung upon its pivot. The arm a^6 carried upon the slide b extends downwardly to one side of the chamber u and is carried back and forth between the side of the chamber and the potatoes which may be therein. 15 This is intended to prevent any clogging of the seed in the chamber.

The bell crank lever a^7 is linked between the dipper and the reciprocating slide and is so arranged that the dipper will be raised 20 and lowered at the proper times, that is, the dipper is lowered as shown in Figs. 3 and 8 when the slide is forward and is raised and emptied into the pocket f as shown in Figs. 6 and 10 when the slide is back.

25 In order that any surplus seed that may be carried by the dipper may be disposed of I have provided a spring actuated plate a^8 operated by a trigger a^9 to give a blow against any such surplus seed and drive it back 30 again into the separation chamber. Thus as the free end of spring actuated plate a^8 comes against the trigger a^9 the plate will be turned upon its pivot against the tension of its actuating spring until it shall pass over the 35 trigger, whereupon the recoil of the spring will throw the plate a^8 forward and thus any surplus seed will be thrown into the separation chamber.

As shown in Fig. 8 the pocket f is open on 40 the side next to the disk h and on its opposite side near the bottom slots are provided, as shown in Fig. 6, so that the lower tines of the forks may enter without obstruction. When the slide b carries a swinging gravity 45 plate a^5 forward an upwardly projecting arm provided upon said plate a^5 is brought against a fixed stop a^{10} as shown in Fig. 3, and thus the free end of the plate is caused to swing forward as shown in said Fig. 3.

50 A view of the bell crank lever n and the spring trigger device o carried upon the slide b for operating the said bell crank lever is shown in the general plan view of the machine, Fig. 2. As the slide is carried forward 55 the lug or wedge shaped piece upon the free end of the spring trigger o passes under the lug on the side of the end of the bell crank lever, the trigger yielding to the resistance of the bell crank while passing under the same.

60 As soon as this wedge shaped lug has been carried beyond the bell crank the trigger flies up against its limiting stop or pin, this pin being placed above the free end thereof. Now upon the return stroke of the slide the 65 wedge-shaped piece is carried against the inclined or bevel-shaped end of the bell crank, and being prevented from upward movement

by its stop the end of the bell crank is forced down and thus the bell crank is caused to withdraw the dog m at the proper time.

It is evident that certain features or parts of my invention might be usefully employed without the others or in connection with forms of mechanism not shown herein. I therefore do not limit myself to the details of construction shown.

Having thus described my invention, I claim as new and desire to secure by Letters Patent—

1. The combination in a potato planter, of 80 a hopper and a pocket for receiving a small amount of seed, a separation chamber between the pocket and hopper and reciprocating mechanism for automatically and positively transporting the seed from the separation chamber to the pocket, substantially as and for the purpose specified.

2. The combination with the pocket and means for successively filling the same with potatoes, of automatically actuated fork devices carried upon a revolving support for lifting the seed from the pocket and dropping the same, substantially as and for the purpose specified.

3. In a potato planter a reciprocating slide, 95 in combination with lever mechanism connected with a shover and a separation chamber through which the shover is actuated positively to carry the potatoes from the hopper backward to the dropping mechanism, 100 substantially as and for the purpose specified.

4. The combination with a stationary pocket adapted to be filled with potatoes, of fork fingers carried upon a disk having a step by step movement, of a cam for operating the fork 105 fingers and means for imparting to said cam a limited rotary movement upon its shaft to withdraw one fork to permit the seed for one hill to drop, while another fork is caused to take hold of the seed in the pocket for another hill.

5. The receptacle or separation chamber provided between the hopper and the pocket and reciprocating pieces or a shover adapted to move the seed in said receptacle toward 115 the dipper, in combination with said dipper which is operated to fill the pocket from the receptacle, said reciprocating pieces or shover being preferably yielding, substantially as and for the purpose specified.

6. The combination with the shover adapted to be moved back and forth in the bottom of the separation chamber, of the weighted pivoted stop or plate carried by the reciprocating slide and adapted to be brought into 125 position to prevent the seed from accumulating or becoming clogged, substantially as and for the purpose specified.

7. The combination with the disk carrying the forks and means for rotating the same step by step, of the cam for operating the forks, said cam being rigidly mounted upon its shaft and an arm rigidly connected to the same shaft on which the cam is mounted and

adapted to be operated by stops carried upon the reciprocating slide to insert and withdraw the forks by giving the cam the desired limited rotary movement back and forth, substantially as and for the purpose specified.

8. The combination with the spring actuated plate carried by the slide, of a trigger arranged to release the plate and permit the same to be thrown forward to clear away any surplus seed, substantially as and for the purpose specified.

9. The combination with the disk moved step by step by a pawl upon the reciprocating slide, of the forks operated by a cam through holes or perforations provided in the disk, and the stationary pocket opposite which the forks are successively brought by the step by step movement of the disk, whereby the seed is carried by the forks acting in succession backwardly and dropped, substantially as and for the purpose specified.

10. The combination with the disk carrying the forks, of the notched disk *k* rigid therewith and mounted upon the same shaft, a pawl carried by the reciprocating slide

adapted to engage with the notches of said disk *k* and the dog *m* operated by the bell crank *n* and the spring trigger *o*, said spring trigger *o* provided with a wedge shaped lug adapted to engage with a lug upon said bell crank being carried upon the said reciprocating slide, substantially as and for the purpose specified.

11. In a potato planter a dipper *e* and means for automatically raising and dipping the same, substantially as and for the purpose specified.

12. In a potato planter the combination with mechanism for carrying the potatoes toward the dropping mechanism, of a dipper *e* and means for raising and dipping and then lowering the same, substantially as and for the purpose specified.

In witness whereof I hereunto subscribe my name this 22d day of October, A. D. 1890.

SAMUEL H. FISH.
